(57) **CLAIM**

The ornamental design for a link assembly with faceted stone, as shown and described.

DESCRIPTION

FIG. 1 is a top perspective view of the link portion of a link assembly with faceted stone according to the new design. The link portion has been shown in isolation in FIG. 1, with the faceted stone removed, for ease of illustration; FIG. 2 is a top perspective view of a link assembly with faceted stone according to the new design, with both the setting portion and the faceted stone shown combined; FIG. 3 is a front view thereof; FIG. 4 is a rear view thereof; FIG. 5 is a right side view thereof; FIG. 6 is a left side view thereof; FIG. 7 is a top view thereof; and, FIG. 8 is a bottom view thereof.
